COMBINED GAME TABLE AND SEATING UNIT

Caine Turner and Connie Marie Turner, both of 9434
Bandera, Los Angeles, Calif. 90002

Filed Sept. 21, 1970, Ser. No. 25,108

Term of patent 14 years

Int. Cl. D6—03

U.S. Cl. D6—45

FIG. 1 is a side elevation of the combined game table and seating unit showing our new design;

FIG. 2 is a plan view thereof; and

FIG. 3 is an end view thereof.

The side of the article not shown is a mirror image of the side shown in FIG. 1.

We claim:

The ornamental design for a combined game table and seating unit, as shown and described.
